UNITED STATES PATENT OFFICE.

EDWIN LUTZ, OF MUNITH, MICHIGAN.

CAN-OPENER.

1,219,971.

Specification of Letters Patent. Patented Mar. 20, 1917.

Application filed August 11, 1916. Serial No. 114,348.

To all whom it may concern:

Be it known that I, EDWIN LUTZ, a citizen of the United States, residing at Munith, in the county of Jackson, State of Michigan, 5 have invented a new and useful Can-Opener; and I do hereby declare the following to be a full, clear, and exact description of the invention, such as will enable others skilled in the art to which it 10 appertains to make and use the same.

The present invention relates to certain new and useful improvements in can openers, and has for its object to provide a device of this character which embodies novel 15 features of construction whereby the top of a can or like container can be easily and quickly removed by a clean cut extending around the sides of the can, thereby avoiding ragged edges and admitting of the contents of the can being removed without difficulty.

Further objects of the invention are to provide a can opener which is simple and inexpensive in its construction, which can 25 be readily applied to a can, which can be manipulated very easily and without danger of cutting or injuring the hands of the operator, and which will make a clean annular cut around the sides of the can so that the 30 top thereof can be swung upwardly and rearwardly, being merely connected to the body of the can by the longitudinal side seam which is easily bent.

With these and other objects in view, the 35 invention consists in certain novel combinations and arrangements of the parts as will more fully appear as the description proceeds, the novel features thereof being pointed out in the appended claims.

40 For a full understanding of the invention, reference is to be had to the following description and accompanying drawing, in which:—

Figure 1 is a top plan view of a can opener 45 constructed in accordance with the invention.

Fig. 2 is a side elevation of the can opener, showing it as applied to a can in position for removing the top therefrom in solid 50 line, the position of the can opener when raising the can top from the can being shown in dotted lines.

Fig. 3 is a transverse vertical sectional view through the jaw of the can opener 55 and the upper portion of a can.

Fig. 4 is a detail perspective view show-

ing a slight modification of the invention, portions being broken away.

Corresponding and like parts are referred to in the following description and 60 indicated in all the views of the drawings by the same reference characters.

The can opener can be conveniently formed, as shown by the drawing, by suitably bending a strip of flat metal, said metal 65 preferably having a slight amount of resiliency. The strip is doubled upon itself at an intermediate point to provide a looped handle 1, each arm of the looped handle being provided at its free end with a curved 70 and substantially semi-circular jaw 2, and the free end of each jaw terminating in an outwardly projecting lateral ear 3. The jaws 2 have an opposed relation and are of a complementary nature so as to fit around 75 the body of a tin can A. The laterally projecting ears 3 also have an opposed relation and are connected by a clamping screw 4.

The curved jaws 2 are provided at substantially the middle portions thereof with 80 longitudinally extending slits within which cutting wheels 5 are arranged, said wheels having sharp peripheral cutting edges, and being mounted upon spindles 6 which may be held in position in any suitable manner. 85 In the present instance longitudinally extending cuts or slits 7 are formed in the jaws 2 both above and below the wheel receiving openings or slots 2^a, the portions of the metal on opposite sides of the slits 90 7 being crimped or bulged laterally in opposite directions, as indicated at 7^a, to receive the spindles 6.

After the opener has been properly applied to a can, with the cutting wheels 5 95 engaging the sides of the can at a point toward the top thereof, the clamping screw 4 is tightened to bring the cutting wheels into a spring engagement with the can. The jaws 2 are then rotated back and forth upon 100 the can by means of the handle 1, thereby causing the sharp edges of the cutting wheels 5 to form an annular cut in the sides of the can, extending entirely around the same and being only interrupted by the 105 longitudinal seam S at the side of the can. If necessary, the clamping screw 4 can be tightened by degrees as the can opener is operated, although the tension produced in the jaws and looped handle by the initial 110 tightening of the clamping screw will ordinarily be sufficient to feed the cutting wheels

in the necessary manner. After the tin has been severed, the tool may be used as a means for forcibly swinging the severed top T of the can upwardly, as indicated by Fig. 5 2. A clean cut is produced without any ragged edges, and the contents of the can can be easily removed without any difficulty.

A slight modification is shown by Fig. 4, in which the jaws 2^b are stiff and resilient 10 so as to be readily flexed around various sizes of cans, and the free ends of the looped handle 1^a are adjustably connected by a suitable latch member 8, thereby enabling the jaws to be set at various distances apart 15 and admitting of the device being adjusted for various sizes of cans. This latch member 8 may be in the form of a resilient strip having a series of notches 9 in one edge thereof, and having hook members 10 at its 20 extremities. Any selected pair of the notches 9 can be placed in engagement with the ends of the handle 1^a, thereby setting the said ends of the handle at a fixed distance apart, depending upon the size of the 25 can. The hook members 10 are then sprung around the edges of the jaws 2 to lock the latch member in position. In other respects the operation of the can opener is exactly as previously described.

30 Having thus described the invention, what I claim as new and desire to secure by Letters Patent, is:—

1. A can opener including a handle, a pair of opposed curved jaws carried by the 35 handle and adapted to fit laterally around the sides of a can body, cutting wheels carried by the jaws and projecting inwardly therefrom, and means for forcibly drawing the jaws toward each other to bring the cutting wheels into operative engagement with the can.

2. A can opener including a looped handle, a pair of opposed curved jaws carried by the respective arms of the looped 45 handle and adapted to fit around the body of a can, cutting wheels carried by the jaws and projecting inwardly therefrom, and means at the free ends of the jaws for forcibly drawing the jaws toward each other 50 to bring the cutting wheels into operative engagement with the can.

3. A can opener including a handle, a pair of opposed curved jaws carried by the handle and adapted to fit around the body 55 of a can, said jaws having openings therein and being provided with longitudinal slits on opposite sides of the opening, the portions of the material adjacent the longitudinal slits being crimped laterally in opposite directions, spindles extending across the openings and received within the said crimped portions of the material, cutting

wheels journaled upon the spindles and arranged within the openings so as to project inwardly from the jaws, and means for forcibly drawing the jaws toward each other to bring the cutting wheels into operative engagement with the can. 65

4. A can opener including a looped handle, a pair of opposed curved jaws carried by the respective arms of the looped handle and adapted to fit around the sides of a can body, an adjustable connection between the arms of the looped handle for setting them at different distances apart, cutting wheels carried by the curved jaws and projecting inwardly therefrom, and means at the free ends of the jaws for forcibly drawing the jaws toward each other to bring the cutting wheels into operative engagement with the can. 70 75 80

5. A can opener including a looped handle, a pair of opposed curved jaws carried by the respective arms of the looped handle and adapted to fit around the body 85 of a can, a latch strip extending across the looped handle and having a series of notches any selected pair of which is adapted to be placed in engagement with the arms of the looped handle to set them at a proper distance apart for the size of can to be operated upon, the ends of the latch strip having hook members adapted to be sprung into engagement with the jaws to hold the strip 90 in position, cutting wheels carried by the jaws and projecting inwardly therefrom, and means at the free ends of the jaws for forcibly drawing the jaws toward each other to bring the cutting wheels into operative engagement with the can. 95 100

6. A can opener including a looped handle, a pair of opposed curved jaws carried by the respective arms of the looped handle and adapted to fit around the body 105 of a can, a latch strip extending across the looped handle and provided with a series of notches any selected pair of which is adapted to be placed in engagement with the arms of the looped handle to set them at a proper distance apart for the size of can to be operated upon, means for locking the latch strip in position, cutting wheels carried by the jaws and projecting inwardly therefrom, and means at the free ends of the jaws for forcibly drawing the jaws toward each other 110 to bring the cutting wheels into operative engagement with the can. 115

In testimony whereof I have signed my name to this specification in the presence of two subscribing witnesses.

EDWIN LUTZ.
